Fig. 5

The dominant features of my design reside in the portions illustrated in solid lines.

I claim:

The ornamental design for a vehicle, as shown and described.
